TAILORING BOARD

Eunice W. Farmer, Webster Groves, Mo.

Filed Sept. 17, 1959, Ser. No. 57,581

Term of patent 14 years

(Cl. D49—1)

FIG. 1.

FIG. 2.

FIG. 3.

FIG. 4.

I claim:

The ornamental design for a tailoring board, substantially as shown.
